METHOD OF MAKING FLUID-TIGHT
PACKING PIECES

Jean Mercier, Neuilly-sur-Seine, France

Application September 2, 1939, Serial No. 293,199
In Luxembourg October 22, 1938

7 Claims. (Cl. 29—156.6)

The present invention relates to a method of making a packing piece having an annular elastic lip adapted to bear against a convex or concave surface so as to form a movable fluid-tight partition along said surface.

The object of my invention is to provide a method of this kind which is both simple and efficient.

According to a feature of my invention, this method includes machining a cylindrical blank so as to form a lip of bevelled axial section, truncating the end portion of said lip, and deforming the truncated end portion so as to cause it to project beyond the cylindrical surface of the lip, while mechanically hardening this truncated end portion.

Preferably, this mechanical hardening is produced by the same operation which effects the desired deformation.

The piece thus prepared is ready to be mounted. It will be observed that the various operations for the manufacture of said packing piece according to the invention are of a very simple nature, and they will thus provide for a most economical manufacture on a large scale.

A preferred embodiment of the present invention will be hereinafter described with reference to the accompanying drawing given merely by way of example, and in which:

Fig. 1 shows the mounting of the blank in a lathe;

Figs. 2 to 4 are partial cross-sections showing three different and successive stages of the packing piece;

Fig. 5 shows the relation of the packing piece with respect to the surface against which it is to be applied.

As shown in Fig. 1, the blank 1 from which the said packing device is to be formed and consisting of a metal bar, a tube, a cylinder or the like, is placed between jaws 2 of a lathe. In Fig. 1, it has been supposed that the packing device has already been rough-cut from a round bar the central part of which has been provided with a hole in order to form the lip 3. It will be noted that the section of the lip decreases gradually from the base 4 to the outer end 5. The external diameter a of the lip is such that the outer cylindrical surface of the piece will fit against the surface upon which it is adapted to slide, with the usual play for such sliding.

Fig. 2 shows in greater detail a portion of a piece which has thus been machined. As will be noted, the section of the lip 3 has now a triangular form, the vertex 5 of the triangle being

the outer edge of the lip. The angle α at the vertex is preferably comprised between 8° and 15° , for instance, for differences of pressure ranging from 0 to 500 kgs. Obviously, care will be taken to give the lip a certain thickness in order that it will have the proper strength. This angle α is usually given a value which is greater according as the diameter, or the difference between the pressures in the two spaces to be separated by the packing piece, or both, are greater.

The outer end of the lip is then cut off by a suitable tool, preferably a diamond milling cutter, in such way as to give the lip, in section, a quadrangular form (Fig. 3), the fourth face 6 thus formed being so inclined as to form with the contact surface 3a an angle α' which is preferably comprised between 30° and 60° .

The surface 6 of the outer edge of the lip is then subjected to a pressure in the direction of the arrow 7, for instance by means of the cutting tool itself, or by any other suitable device, such as a roller or a small wheel running on said surface 6, thus providing for the required deformation. (This deformation may be slight; with a packing piece having a diameter of 40-50 mm., for instance, it may produce a projection of the truncated end portion of about $\frac{1}{10}$ to $\frac{1}{10}$ mm. beyond the cylindrical surface of the lip.) The periphery of said roller or wheel should preferably be smooth, and it must be so located with reference to the packing piece as to roll upon the entire length of the edge, thus producing the desired projection and deformation. This may have a certain importance when the packing piece is mounted on a lathe and when it is desired to obtain the deformation while at the same time continuing to rotate the piece on the lathe. This method of operation is quite simple and economical, and moreover, there is no risk of tearing off the material of the lip. It is evident that the roller tool will be applied against the packing piece with the proper pressure.

The pressure thus exerted will cause a deformation of the outer part 7 of the lip, and hence the latter will form a nose or a beak or simply an outstanding portion which projects, as shown in Fig. 4, beyond the cylindrical surface 3a of the lip.

This deformation serves not only to form the nose 7, but also to produce a surface hardening of the end part 7 of the lip. Thus the metal of the packing piece, in this part, a greater hardness and rigidity.

When the packing piece is then mounted on the devices between which a fluid-tight joint is to be obtained, the lip 3 becomes slightly curved

below the hardened end part, as shown in Fig. 5. In fact, the nose 7 which projects from the surface 3^a is pressed back by the contact surface 8^a of the device 8.

This forms a small space between the surfaces 3^a and 8^a below the nose 7, and it is only this sharp edge 7^a of this nose that is applied with force against the contact surface 8^a, thus affording the desired fluid-tight joint.

Obviously, the invention is not limited to the embodiment herein described and represented, which is given solely by way of example.

For instance, the packing piece may consist of any elastic material, and chiefly of a suitable metal or alloy such as bronze, nickel or glucinium bronze, steel bronze, or other suitable metals or alloys (silver, brass, copper, etc.). A packing piece of rubber or the like may also be employed, in which the end of the lip can be metallized.

Having now described my invention, what I claim as new and desire to secure by Letters Patent is:

1. A method of manufacturing a packing piece of the type described which comprises starting from a cylindrical blank, machining said blank so as to form, at one end thereof, an annular lip of bevelled axial section, cylindrical on one side thereof and conical on the other side, cutting off the end portion of said annular lip so as to truncate it along a conical surface coaxial with said conical side of said lip and of the same direction but of greater apex angle, deforming the truncated end portion of said lip so as to project beyond the cylindrical surface thereof in the direction of the part with which the packing piece is to cooperate in a fluid-tight manner and mechanically hardening this end portion of the lip.

2. A method of manufacturing a packing piece of the type described which comprises starting

from a cylindrical blank, machining said blank so as to form, at one end thereof, an annular lip of bevelled axial section, cylindrical on one side thereof and conical on the other side, cutting off

6 the end portion of said annular lip so as to truncate it along a conical surface coaxial with said conical side of said lip and of the same direction but of greater apex angle, and deforming the truncated end portion of the lip so as to cause 10 it to project beyond the cylindrical face thereof, in the direction of the part with which the packing piece is to cooperate in a fluidtight manner, this deforming operation being performed in such manner as to harden this end portion of the 15 annular lip.

3. A method according to claim 2 in which the deforming operation is performed by means of the same tool that has been used for cutting off the end portion of the annular lip.

20 4. A method according to claim 2 which comprises performing the machining operation on a lathe, cutting off the end portion of the lip as the piece is still on the lathe, and deforming the truncated end portion of the lip by means of a tool including at least one roller arranged to run 25 on the annular edge formed when cutting off the end of the lip.

5. A method according to claim 1 in which the deformed end portion of the lip is caused to project beyond the cylindrical surface of the lip a distance ranging from one to two tenths of a millimeter for a packing piece of a diameter ranging from 40 to 50 millimeters.

30 6. A method according to claim 2 in which said blank is made of metal.

35 7. A method according to claim 2 in which said blank is made of rubber having a metallized end portion.

JEAN MERCIER.
